(57) **CLAIM**

I claim the ornamental design for a gas cooktop, as shown and described.

DESCRIPTION

FIG. 1 is a Perspective view of a gas cooktop showing my new design;

FIG. 2 is a Front view thereof;

FIG. 3 is a Back view thereof;

FIG. 4 is a Left-side view thereof;

FIG. 5 is a Right-side view thereof;

FIG. 6 is a Top elevation view thereof; and,

FIG. 7 is a Bottom view thereof.

The broken lines are for the purpose of illustrating portions of the article that form no part of the claim.

1 Claim, 5 Drawing Sheets
